CONDUIT CLIP

Raymond L. Martz, Palatine, Ill., assignor to Minerallac Electric Company, Chicago, Ill.

Filed June 26, 1972, Ser. No. 247,910

Term of patent 14 years

Int. Cl. D8—08

U.S. Cl. D8—235

FIG. 1 is a perspective view of a conduit clip embodying my new design with a conduit and a supporting structure being shown in broken line for illustrative purposes.

FIG. 2 is a plan view of the conduit clip shown in FIG. 1.

FIG. 3 is a side elevational view of the conduit clip shown in FIG. 1.

FIG. 4 is an end elevational view of the conduit clip shown in FIG. 1.

I claim:

The ornamental design for a conduit clip, as shown and described.
